UNITED STATES PATENT OFFICE

2,685,380

STOPPER

Axel Moeller, Racine, Wis., assignor to Moeller Mfg. Co., Racine, Wis., a corporation of Wisconsin

Application September 13, 1950, Serial No. 184,610

1 Claim. (Cl. 215—53)

1

This invention appertains to bottle and jar stoppers or closures, and is an improvement over my prior Patents Nos. 2,347,835, dated May 2, 1944; 2,292,149, dated August 4, 1942, and 2,315,538, dated April 6, 1943.

One of the primary objects of my present invention is to provide an expandable stopper for large mouthed jars, such as so-called picnic jugs or jars, for efficiently sealing such jars and jugs and at the same time permit the convenient insertion and withdrawal of the stopper in the jar or jug mouth.

Another salient object of my invention is to provide a novel elastic and resilient stopper body of an annular form with novel means for supporting and compressing the body longitudinally to insure the proper engagement thereof with the interior of the neck of the jar or jug and particularly at the pouring lip portion thereof.

A further object of my invention is to provide means for forming the annular body, whereby when the body is compressed longitudinally, it will initially expand radially in an outward direction at a point above the lower end thereof, whereby to insure the proper sealing engagement of the body with the neck adjacent to the mouth thereof.

A further important object of the invention is to provide novel top and bottom supporting and compressing plates for the annular body, whereby not only will the body be effectively supported, but whereby the body will be properly guided into its neck engaging position upon compression of the body.

A further object of my invention is to provide a flexible bottom wall integral with the resilient body, the wall having a centrally disposed opening for snugly receiving the stud or shank carried by the bottom supporting and compression plate, whereby the body will be accurately centered in the stopper relative to the compression plates and adjusting means and whereby a protecting wall is formed for preventing the seeping of liquids and other foreign matter into the bottom of the body and around the stem and said adjusting means.

With these and other objects in view, the invention consists in the novel construction, arrangement and formation of parts, as will be hereinafter more specifically described and claimed and illustrated in the accompanying drawing, in which drawing,

Figure 1 is a central vertical sectional view through the improved stopper showing the same inserted in the mouth of a jug.

2

Figure 2 is a similar view, but showing the stopper in its expanded position for sealing the jug.

Figure 3 is a fragmentary top plan view of the stopper.

Figure 4 is a horizontal sectional view through the stopper taken on the line 4—4 of Figure 1 looking in the direction of the arrows.

Referring to the drawing in detail, wherein similar reference characters designate corresponding parts throughout the several views, the letter S generally indicates the improved stopper, which is particularly useful for association with a large mouthed jug or jar J.

15 The jar or jug J forms no part of the present invention and can include an insulated wall 5 and a neck 6. As illustrated, the neck 6 can be provided with an inturned bead 7 at its pouring lip, but it is to be understood that the stopper S can be effectively used with jars or jugs having a straight neck in lieu of the inturned bead.

The stopper S includes the annular resilient and compressible body 8 preferably formed from rubber or the like and the outer surface of the body can be provided with the annular ribs 9 in accordance with my prior Patent No. 2,315,538. Formed integral with the lower end of the stopper body 8 is a flexible sealing and centering wall 10 and this wall 10 is provided with an axially disposed opening 11 for a purpose which will later appear. If desired, the wall 10 can be thickened for reinforcement, as the same approaches the opening 11. It is to be also noted that the annular body 10 adjacent to its lower end is gradually thickened toward the bottom wall 10, as at 12, the purpose of the thickened portion 12 will also later appear.

In conjunction with the annular body 8, I employ upper and lower compression and supporting plates 13 and 14. The plates are preferably but not necessarily formed from stainless steel, and these plates are of a special form as will be described. Secured to the axial center of the lower plate 14, is the threaded stem or shank 15, and the stem has threaded thereon the sleeve nut 16. The upper plate 13 is provided with an axially disposed opening which slidably receives the sleeve nut 16. The shank 15 can be rigidly connected to the lower plate 14, in any desired way, but as shown, in Figures 1 and 2, the shank is preferably flanged over the top and bottom faces of the plate 14, as at 17, to form a rigid structure and to prevent the leakage of material between the shank 15 and the plate 14. The shank is also provided with an annular seat 18.

Connected to the upper end of the sleeve nut 16, by means of a pivot pin 19, is the operating cam 20 and the cam is adapted to engage the upper face of the top plate 13. If desired, a wear washer 21 can be placed between the cam 20 and the plate 13 and the plate 13 can be centrally depressed as at 22, to receive the washer. An annular upstruck bead 22' surrounds the depressed portion 22 and forms a stop for the downward movement of the cam 20 and determines the setting of the locked position of the cam.

As in my previous patents, the cam 20 can be initially used for turning the sleeve nut 16 to bring the plates 13 and 14 toward and away from one another for adjusting the body 8 to an approximate desired diameter and after such initial adjustment, the cam 20 can be swung to its lowered position, as shown in Figure 2, for longitudinally compressing the body 8 to expand the same into the desired sealing contact with the interior wall of the neck 6.

Now referring to the top plate 13, the same is provided with an annular channel 23, adjacent to but spaced from its periphery, which forms a seat for the upper end of the annular body 8. Particular attention is called to the fact that the upper wall 24 of the channel inclines upwardly and outwardly toward the periphery of the plate 13 and the purpose of this will also later appear. The channel 23 is above the plane of the main portion of the plate, and hence the upper edge of the body 8 is above the plane of the major portion of the plate.

The lower plate 14 is provided with an upwardly pressed annular channel 25 and the edge of this channel inclines downwardly and outwardly to provide an inclined supporting lip 26, on which a portion of the lower edge of the body 8 rests when the body is compressed.

In operation of the stopper, the cam lever 20 is swung to a vertical position, as shown in Figure 1, after which the stopper is bodily inserted within the neck 6 of the jar or jug J. By turning the cam lever 20, as heretofore stated, the body 8 can be initially compressed and after which the cam lever can be swung down to the operative position as shown in Figure 2, and the body 8 will then be compressed to its greatest extent and into intimate contact with the neck 6. It is highly desirable that in the longitudinal compression of the body 8, that the body intimately contact the neck and seal the same at the upper end thereof. As the body 8 is thickened at its lower end, as at 12, the body will tend to bow initially above this thickened portion, and due to the inclined wall 24 of plate 13 and the inclined lip 26 of plate 14, the body will tilt to a limited extent on the plates so as to permit the proper outward flexing of the body 8. This forms an exceptionally efficient structure and the desired seal is obtained.

The opening 11 in the flexible wall 10 snugly receives the seat 18 of the shank 15 and this opening 11 can be of a slightly less diameter than the seat, if desired, so that a sealing engagement will be had between the wall of the opening 11 and the seat 18. This effectively prevents the entrance of foreign matter into the interior of the body 8 through the bottom of the stopper. The wall 10 and the opening 11 is highly desirable, in that the same provide an accurate centering means for the body 8, the shank 15 and the plate 14. Obviously, the nut sleeve 16 correctly centers the top plate 13.

Changes in details may be made without departing from the spirit or the scope of this invention, but what is claimed as new is:

A stopper comprising an annular compressible body, a bottom supporting and compressing plate, a top compression plate, adjusting means connecting the plates including an axially disposed shank on said bottom plate having an annular seat adjacent to said plate, said bottom plate having an upstruck annular bead terminating in an outwardly and downwardly inclined lip receiving the lower edge of the body and said upper plate having an annular channel receiving the upper end of the body, said channel being provided with an outwardly and upwardly inclined top wall for engaging the extreme upper edge of the body, said lip and said inclined wall forming guides for the outward flexing of the body upon the adjustment of the plates toward one another, and said body being interiorly thickened toward its lower end directly above the bead and its lip, said thickened portion terminating short of the central horizontal axis of the body, and a flexible bottom wall on said body having an axial opening snugly engaging said seat, whereby, upon the adjustment of the plates toward one another, the body will bow initially above said thickened portion and will tilt to a limited extent on the inclined lip and top wall of the respective plates.
